UNITED STATES PATENT OFFICE

NEAL S. OLSEN, OF BROOKLYN, NEW YORK, ASSIGNOR TO UNIVERSAL OIL PRODUCTS COMPANY, OF CHICAGO, ILLINOIS, A CORPORATION OF SOUTH DAKOTA

APPARATUS FOR DEPHLEGMATION

Application filed July 11, 1927. Serial No. 204,688.

The present improvements relate more particularly to apparatus for the dephlegmation of vapors whereby those not of the desired characteristics are condensed and separated from those which are of the desired characteristics, those not of the desired characteristics being returned, if desired, for re-treatment.

The present invention is applicable to the dephlegmation of vapors of any sort, and in one specific embodiment it is particularly applicable to the dephlegmation of hydrocarbon oil vapors produced in the cracking or distillation of hydrocarbon oil.

In order to secure efficient fractionation of cracked hydrocarbon oil vapors it has been found advantageous to provide a process and apparatus in which, first, there is maximum intimate contact between vapors and liquid, and second, the maintenance of a pool of liquid at various stages in the dephlegmating instrumentality whereby light fractions entrained in the liquid have an opportunity i. e. time, to be released.

The present invention is particularly designed to provide for intimate contact between liquid and vapors and the maintenance of a pool or pools of liquid.

As a feature of the present invention, there is provided a horizontally disposed dephlegmator wherein the vapors are successively caused to have a back and forth travel and wherein the vapors bubble through a pool of liquid during said back and forth travel. During the travel of the vapors through the dephlegmating instrumentality these vapors not having the desired characteristics will be condensed as reflux condensate, while those which have been sufficiently converted will be removed and collected as the desired product.

One of the objects of the present invention is to provide a process wherein the vapors are forced to pass repeatedly through a

cooling liquid maintained in the dephlegmator for that purpose.

As a feature of the present invention, I provide for the return of regulated portions of the reflux condensate to any desired portion of the body of liquid maintained in the dephlegmator. I also provide for the withdrawal of reflux condensate at separated points longitudinally of the dephlegmating instrumentality whereby certain portions of the reflux condensate produced by the dephlegmation may be withdrawn and diverted from the process, for instance, such reflux condensate may be diverted to storage.

The utility as well as other objects and advantages of the invention will be more particularly brought out in the following description.

In the drawing, the single figure is a diagrammatic elevational view with parts in vertical section of apparatus in which the invention may be carried out.

In the cracking of hydrocarbon oils as practiced today, one of the essential features of a successful process resides in the efficient dephlegmation or fractionation of the cracked vapors so as to secure a separation of the sufficiently cracked fractions (which are subsequently condensed and collected as the desired product) from those which are insufficiently cracked. These lighter vapors, during dephlegmation, are condensed and preferably returned to the heating zone for re-treatment combined, if desired, with charging stock.

Referring more in detail to the drawing, 1 designates a horizontal shell type dephlegmator or reflux condenser inside of which may be placed a horizontal partition 2 so attached to the side walls of the horizontal dephlegmator 1 as to form a liquid seal and so perforated that short goosenecks 3 can be attached thereto in such a manner as to project upward therefrom. These goosenecks are attached to partition 2 at stated intervals 80

from one end to the other. Interposed between predetermined spaced goosenecks are overflow pipes 4 which are also attached to the partition 2 and which project upwardly therefrom for a height such as to regulate the depth of the liquid pool maintained on the partition.

The space below the partition 2 may be divided by upright or transverse partitions 5 into a number of spaced and separated compartments. The lower portion of the partitions 5 may be preferably provided with perforations or apertures 5', whereby liquid overflowing from the pool on partition 2 through the overflow pipe 4 may flow along the lower wall of dephlegmator 1 passing out through the last drawoff pipe 6.

The space above the partition 2 may be likewise divided into transverse sections or compartments by means of partitions 7 which extend from the top downwardly toward the partition 2, terminating at a point above the partition 2 where they form a liquid seal between sections. In other words, the lower extremity of each partition 7 terminates at a point below the top of each overflow pipe 4 whereby said extremity is below the liquid level of the pool of liquid maintained on partition 2. These partitions 7 may, if desired, be so placed longitudinally as to form a liquid seal adjacent each overflow pipe 4, the partitions 5, on the other hand, being so located as to extend downwardly on the opposite side of the overflow pipes 4 in a longitudinal line. The goosenecks 3 may fill the space in each section not occupied by the overflow pipe 4, said goosenecks extending upwardly to a point above the top of the overflow pipes 4 and then downwardly to a point below the top of said overflow pipes 4, which point, when the dephlegmator is in operation, will be below the surface of the body of liquid held on the partition 2. It will be noted that the liquid held on the partition 2 will be one continuous body and will not comprise separate pools in each section.

Vapors which may evolve in a concurrently operating or distilling process and which may comprise any kind of vapors, may be introduced through the vapor inlet line 8, which may be controlled by valve 8'. This vapor inlet line 8 may be disposed at one end of the shell 1 below the partition 2. From the top of the shell 1 above the last section from the inlet 8 a dome 9 may extend upwardly from the top of which may project the vapor line 10 controlled by valve 11, which vapor line may communicate with a final condenser (not shown).

The charging line 12 through which may be interposed any desired cooling medium, such as regulated portions of charging stock may communicate with a coil 16 disposed in the vapor space of the dome 9, functioning to interchange heat and regulate the tempera-

ture of the vapors exiting through the vapor line 10. Or by closing valve 15, the liquid introduced through line 12 may be introduced directly through the line 13 in which may be interposed a valve 14. When charging through the coil 16, the oil after circulating through the coil may continue through line 17, in which may be interposed valve 17' to the heating zone of a cracking process (not shown) if the dephlegmator is connected to the cracking process, or to any other medium desired. All or regulated portions may be withdrawn through the line 17a controlled by 17b if desired.

The intake of pump 18 is connected to the reflux line 6, and may take the reflux condensate from the bottom of the dephlegmator 1 through line 6 direct or through lines 6' controlled by valves 20. The discharge from the pump 18 through line 21 may be directed into the charging line 17 going to the cracking zone, or, if desired, the valve 22 may be closed and the valve 23 in line 24 opened whereby all or regulated portions of the reflux condensate may be diverted from the line 21 into the line 24 rather than passed through the line 17. The line 24 returns regulated portions of the reflux condensate to the upper portion of the horizontal shell 1 through the branch lines 25 in which may be interposed valves 26. It is to be noted that there is a branch 25 communicating with each of the compartments produced by the transverse partitions 7. In some instances it may be desirable to withdraw certain portions of the reflux condensate directly from the shell 1, in which event the valves 27 in the drawoff lines 28 may be manipulated in an obvious manner.

In one embodiment of the invention an operation may be described as follows:

Heated vapors, for instance, from a concurrently operating, distilling or cracking process may enter the dephlegmator through vapor inlet line 8. During the travel of the vapors in the dephlegmator, said vapors are caused to have an up and down travel, first through the first lower section, then up through the goosenecks 3 into the first upper section, thence down through the first overflow pipe 4 into the second lower section, thence up through the goosenecks 3 into the second top section and so on to the last top section where the vapors still remaining uncondensed pass out through the vapor line 10. The vapors which are condensed flow onto partition 2 as liquid and overflow through the overflow pipes 4 to the bottom of the shell, being eventually drawn through the reflux line 6. In this manner, the vapors discharge below the liquid level of the pool maintained on the partition 2 whereby intimate contact between vapors and liquid occurs. At the same time vapors are prevented from channelling due to the liquid seals

formed at the bases of the partitions 7. In addition, the pool of liquid maintained on the partition 2 will be subjected to a certain amount of reboiling due to the heat of the vapors striking against the bottom of said partition, thus relieving from the pool any light fractions which may be entrained therein. The maintenance of this pool also complies with one of the requirements of efficient dephlegmation, that maximum time be permitted for the liquid to be subjected to fractionating conditions.

Instead of returning all of the reflux condensate through the line 17, all or a portion of same may be intermittently diverted through the line 24 and introduced into any of the compartments formed by the transversely disposed partitions 7. This permits of a more closely controlled fractionation where such would be desirable.

By the present invention the known favorable conditions for efficient fractionation are provided for, and the temperature and characteristics of the vapors exiting through the vapor outlet pipe 10 can be definitely controlled.

The process and apparatus may be maintained under superatmospheric, atmospheric or sub-atmospheric pressure.

1. I claim as my invention:

1. Apparatus for dephlegmation, comprising a shell, a partition therein dividing said shell into upper and lower sections, means in the upper and lower sections dividing same into longitudinally separated compartments, upwardly projecting vapor risers attached to the first mentioned partition, separate liquid overflow pipes also attached to said first mentioned partition and projecting upwardly therefrom, the outlets from said vapor risers being disposed below the plane of the upper ends of the liquid overflow pipes whereby a pool of liquid is maintained on said first mentioned partition, means for withdrawing reflux condensate from the bottom of the shell, and means for diverting regulated portions of the reflux condensate withdrawn from the bottom of the shell to said separated compartments in the upper section.

2. Apparatus for dephlegmation, comprising a horizontally disposed shell, a partition therein dividing said shell into upper and lower sections, means comprising partitions in the upper and lower sections dividing same into longitudinally separated compartments, upwardly projecting vapor risers taking the form of goosenecks attached to the first mentioned partition, separate liquid overflow pipes also attached to said first mentioned partition and projecting upwardly therefrom, the outlets from said vapor risers being disposed below the plane of the upper ends of the liquid overflow pipes whereby a pool of liquid is maintained on said first mentioned partition, means for withdrawing reflux con-

densate from the bottom of the shell, and means for selectively diverting regulated portions of the reflux condensate withdrawn from the bottom of the shell to said separated compartments in the upper section.

3. A dephlegmating apparatus comprising a horizontally disposed shell, a partition dividing said shell into an upper section and a lower section, additional partitions dividing the upper and lower sections into longitudinally separated compartments, means for passing vapors through said compartments, means for withdrawing condensate from the compartments of said lower section, and means for introducing withdrawn condensate into any selected compartment of said upper section.

4. A dephlegmating apparatus comprising an elongated shell, a horizontal partition dividing said shell into a lower section and an upper section, additional partitions dividing said upper section into a plurality of upper compartment means for introducing vapors to said lower section and for passing the same through said upper compartments in series, means for collecting a pool of condensate in each of said upper compartments, means for causing the vapors passing through said upper compartments to percolate through said pools, means for overflowing condensate from said upper compartments into said lower section, means for withdrawing condensate from said lower section, and means for introducing withdrawn condensate into the last upper compartment through which the vapors pass.

5. A dephlegmating apparatus comprising an elongated shell, a horizontal partition dividing said shell into a lower section and an upper section, additional partitions dividing said upper section into a plurality of upper compartments, means for introducing vapors to said lower section and for passing the same through said upper compartments in series, means for collecting a pool of condensate in each of said upper compartments, means for causing the vapors passing through said upper compartments to percolate through said pools, means for overflowing condensate from said upper compartments into said lower section, means for withdrawing condensate from said lower section, and means for introducing withdrawn condensate into any selected compartment of said upper section.

6. A dephlegmating apparatus comprising an elongated shell, a horizontal partition dividing said shell into a lower section and an upper section, additional partitions dividing said upper section into a plurality of upper compartments, means for introducing vapors to said lower section and for passing the same through said upper compartments in series, means for collecting a pool of condensate in each of said upper compartments, means for

causing the vapors passing through said upper compartments to percolate through said pools, means for overflowing condensate from said upper compartments into said lower 5 section, means for withdrawing condensate from said lower section, and means for introducing withdrawn condensate into the last upper compartment through which the vapors pass, and additional means for introducing a 10 second liquid cooling medium to said last compartment.

In testimony whereof I affix my signature.
